CLAIM

I claim the ornamental design for a front face for a handset, as shown and described.

DESCRIPTION

FIG. 1 is a top plan view of the front face for a handset;

FIG. 2 is a left side view thereof;

FIG. 3 is a front view thereof;

FIG. 4 is a right side view thereof;

FIG. 5 is a bottom plan view thereof; and,

FIG. 6 is a perspective front view thereof.

The portion of the front face for a handset shown in broken lines is for illustrative purposes only and forms no part of the claimed design.
